UNITED STATES PATENT OFFICE

JOHN B. PITTS, OF LOUISVILLE, KENTUCKY

MOBILE DISPLAY RACK

Application filed December 5, 1928. Serial No. 323,847.

The present invention relates to a display rack and has for its prime object to provide a rack of this nature whereby groceries and the like may be displayed thereon in an exceedingly compact and convenient manner and wherein the rack may be easily moved from place to place.

Another very important object of the invention resides in the provision of a rack of this nature including a mobile base having a revolving structure thereon with shelves for display purposes.

A still further very important object of the invention resides in the provision of a rack of this nature with a plurality of detachable shelves and partitions whereby the rack may be easily cleaned and maintained in an entirely sanitary condition.

A still further very important object of the invention resides in the provision of a rack of this nature which is exceedingly simple in its construction, inexpensive to manufacture, strong and durable, light, thoroughly efficient and reliable in use, and otherwise well adapted to the purpose for which it is designed.

With the above and numerous other objects in view as will appear as the description proceeds, the invention resides in certain novel features of construction, and in the combination and arrangement of parts as will be hereinafter more fully described and claimed.

In the drawings:

Figure 1 is an elevation of the rack embodying the features of my invention,

Figure 2 is a horizontal section taken therethrough looking downwardly,

Figure 3 is a perspective view of one of the partitions,

Figure 4 is an enlarged detail section taken substantially on the line 4-4 of Figure 5,

Figure 5 is a vertical section through the lower portion of the rack,

Figure 6 is a top plan view of the base showing the central standard section,

Figure 7 is a perspective view of one of the radial shelf supports, and

Figure 8 is an enlarged detail section taken substantially on the line 8-8 of Figure 5.

Referring to the drawing in detail it will

be seen that the letter B denotes generally a rectangular base which is made up of side angle bars 5 and cross or end angle bars 6 connected therewith. Diagonal cross braces 7 extend between the corners of the base and have a socket 8 mounted thereon for supporting a vertical central standard 9.

A circular track 10 is mounted on the braces 7 concentrically about the standard 9. The track 10 is preferably constructed of angle bar material. An elongated vertical tube 11 is disposed about the standard 9 to rotate thereabout.

A plurality of collars 12 are mounted on the tube 11 at spaced intervals. A plurality of spokes 14 preferably of sheet iron, T-shaped in cross section radiate from the collars 12 and have notches 15 to receive uprights 16 which are also of sheet iron, and T-shaped in cross section. Annular angle iron members 17 extend about the tube 11 being formed in sections between the uprights 16. Foraminous shelves 18 rest on the bars 14 and 17 and foraminous partitions 19 rest on the bar 14 to be disposed between the various shelves as is quite apparent in Figure 1, when taken with Figure 2.

On the lowermost annular bar 17 there are mounted rollers 20 which ride on the track 10 when this rack is revolved. The base B is mounted on a plurality of casters 21 preferably one in each corner thereof. At the upper ends of the uprights 16 there is an annular bracing band 22 and it is preferable to provide a cap 23 over the upper end of the tube 11.

This device is designed primarily to save space and time is especially useful in grocery stores since it can be filled with goods and hauled to any part of the store desired. The structure is highly sanitary since the same is made of foraminous sheet material and iron and steel and is attractive in its appearance as a store fixture.

Another very good feature is that the rack may be revolved and thus can be turned to any position to obtain any kind of canned goods or merchandise the customer may wish to purchase. Obviously the device would specially be valuable in the self service stores

since the customer can turn the rack around and select the goods on the particular shelf desired.

It is thought that the construction, utility and advantages of this invention will now be clearly understood without a more detailed description thereof.

The present embodiment of the invention has been disclosed in considerable detail merely for the purposes of exemplification since in actual practice it attains the features of advantage enumerated as desirable in the statement of the invention and the above description.

It is apparent that changes in the details of construction, in the combination and arrangement of parts may be resorted to without departing from the spirit or scope of the invention as hereinafter claimed or sacrificing any of its advantages.

Having thus described my invention, what I claim as new is:

1. In combination, a mobile base, a standard rising from the base, a tube revoluble on the standard, a plurality of spaced collars on the tube, bars radiating from the collars and tubes, and being T-shaped in cross section, and having notches at their outer ends, uprights of T-shape in cross sections, having flanges in said notches, arcuate bars between the uprights, shelves resting on said first and second mentioned bars between said uprights, a plurality of partitions resting on the first mentioned bars between the tube and the respective uprights, an annular track fixed to said base concentric with said standards, and wheels on the lowermost arcuate bars ridable on said track.

2. In combination, a mobile base, a standard rising from the base, a tube revoluble on the standard, a plurality of spaced collars on the tube, bars radiating from the collars and the tube and being T-shaped in cross section and having notches at their outer ends, uprights of T-shaped cross section having flanges fixed in said notches, arcuate bars between the uprights, shelves resting on the first and second mentioned bars, partitions resting on the first mentioned bars between the shelves, said shelves and partitions being formed of foraminous material, an annular track formed of angle iron material fixed on the base, concentric with the standard, wheels on the lowermost arcuate bars ridable on the track.

In testimony whereof I affix my signature.
JOHN B. PITTS.
